Primary Examiner — Michael C Stout*Assistant Examiner* — Fritzgerald L Butac*(74) Attorney, Agent, or Firm* — Fish & Richardson P.C.(57) **CLAIM**

The ornamental design for a perforating gun contact ring, as shown and described.

DESCRIPTION

FIG. 1 is a top, left perspective view of a perforating gun contact ring, according to our new design.

FIG. 2 is a top, right perspective view of the perforating gun contact ring of FIG. 1.

FIG. 3 is a right view of the perforating gun contact ring of FIG. 1.

FIG. 4 is a left view of the perforating gun contact ring of FIG. 1.

FIG. 5 is a front view of the perforating gun contact ring of FIG. 1.

FIG. 6 is a back view of the perforating gun contact ring of FIG. 1.

FIG. 7 is a top view of the perforating gun contact ring of FIG. 1; and,

FIG. 8 is a bottom view of the perforating gun contact ring of FIG. 1.

The broken lines show portions of a perforating gun contact ring that form no part of the claimed design.
